UNITED STATES PATENT OFFICE.

JOHN E. HUME AND GEORGE S. THOMPSON, OF CLINTON, MASSACHUSETTS.

FILLING-CHANGER.

1,133,286.

Specification of Letters Patent. Patented Mar. 30, 1915.

Application filed September 27, 1912. Serial No. 722,618.

To all whom it may concern:

Be it known that we, JOHN E. HUME and GEORGE S. THOMPSON, citizens of the United States, both residing at Clinton, in the county of Worcester and State of Massachusetts, have invented a new and useful Filling-Changer, of which the following is a specification.

This invention relates to weft replenishing looms having a stationary magazine for the bobbins or filling carriers in a plurality of sets, each set having a different color from the others.

The principal objects of the invention are to simplify the construction and reduce the number of parts, particularly the means for effecting the change of the filling, and the constant supply of bobbins or filling carriers to the loom from the proper compartments of the magazine; to provide an easily adjustable and smoothly operating machine for this purpose; to bring the bobbin that is to be transferred nearer to the shuttle that is to receive it, thereby securing an evener and surer transfer of the same; to drop the bobbins into the boxes in an improved and simplified manner at a time when the transferer is not operating; to time the different motions to perform their work so that the bobbin has time to be properly adjusted in the box before the transferer is called upon to operate it, so that there is ample time to accomplish the transfer of the bobbin to the shuttle, and that action can be performed evenly and accurately. In this way the loom can be run faster than with the ordinary constructions.

The invention also involves operating means for several of the parts as will appear hereinafter.

Reference is to be had to the accompanying drawings in which—

Figure 1 is a view of one end of a loom of this character showing a preferred embodiment of this invention; Fig. 2 is a similar view at the opposite end; Fig. 3 is a front elevation of a portion of the loom; Fig. 4 is an end elevation of certain details of the magazine; Fig. 5 is a plan view of the boxes; Fig. 6 is a view of parts shown in Fig. 2, but in a different position; and Fig. 7 is a sectional view of the same on the line 7—7 of Fig. 6.

The invention is shown as applied to a

loom frame 10 of well known construction, having a magazine 11 fixed thereon provided with a plurality of compartments 11^a for the filling carriers or bobbins of the several colors or other characteristics. The loom is shown as provided with a shaft 15 which passes from one end to the other at the bottom. This shaft is operated to oscillate from the box motion by means not shown, and is provided with an arm 16 connected by a link 17 with the usual shuttle box lever 18 for operating the shuttle boxes. The shaft 15 is also provided with an arm 20 extending upwardly and having at the upper end thereof a gear segment 21. This gear segment meshes with a rack 22 which is connected by a rigid arm 23 with the set of boxes 24 to give said boxes a horizontal rectilinear reciprocation under the magazine 11 as the shaft 15 oscillates. There are any desired number of boxes in this set, one for each color or other character of yarn used. The boxes are provided with end plates 24^a, 24^b and 24^c, so shaped as to guide the yarn properly into position. These boxes slide on a plate 25 fixed on the loom close to the shuttle box. This plate is flat on top and is preferably provided with guides 26 for the boxes 24, and is curved on its under side to accommodate the swing of the lay. This plate is also provided with a passage 27 therethrough to allow the bobbin and thread to pass through it when changing the bobbin to the shuttle. The boxes 24 work in conjunction with the shuttle boxes on account of the fact that both are connected with the same shaft 15 through the arms 16 and 20, respectively. Therefore it will be seen that the color that is weaving can be made always to be located under the transferer 30 ready for being transferred to the shuttle. The boxes 24 are of such width that when one box is positioned under the transferer 30, the other box 24 is positioned under the magazine 100 compartment containing bobbins with weft thread of the proper color.

On the frame of the loom is a bracket on which is pivoted a feeler 28 of any ordinary construction, preferably the well known "Crompton mechanical feeler", which engages the filling on the bobbin and travels invariably with it. When the filling on the bobbin moves into contact with the feeler in opposition to a spring 28^a on a rod 290, it 110

oscillates the rod and operates an arm 29 carried by an arm 29^a to withdraw said arm 29 from contact with a rod 34. The rod 290 corresponds with shaft 20 of U. S. 5 Patent to Ryon, No. 972,722 on the "Crompton mechanical feeler", and the spring 28^a corresponds with the spring 21 of the Ryon patent. The arm 29 is actuated in the same way as the rod 24 of the Ryon patent, but, 10 of course, it has a different effect as explained herein.

The operation of these parts is as follows: On a longitudinal shaft 31 at the bottom of the machine is a cam 32 operating a lever 33 15 which is connected with a rod 34 extending upwardly in the loom and imparts to this rod a vertical reciprocating motion. Every time the lay beats up, the filling on the bobbin in the shuttle engages the feeler 28 and forces the feeler, together with arm 29, 20 backwardly. This keeps the arm 29 out of contact with the upper end of the rod 34 at this time and allows that rod to reciprocate vertically without touching a finger 36.

25 When, however, the filling is substantially exhausted, the bobbin cannot push the feeler to cause it to rock rod 290 and consequently the end of the arm 29 is left in contact with the rod 34. This forces rod 34 to engage the 30 under side of a finger 36 on its next rise and lift said finger. This finger 36 is secured on a horizontal shaft 35 on which is another finger 36^a which lifts the trip 37 on that one of the boxes 24 which is in position to deliver a bobbin. This trip 37 slides vertically in the end of the box and is held in its elevated or depressed position by friction. When tripped by finger 36^a it moves up and lifts an arm 38 on a shaft 39 which is provided with another arm 40 which extends 40 downwardly and is connected with a rod 41 by a guide arm 42 and moves said rod laterally under a plate 43 on rod 44, when the shaft 39 is rocked by the lifting of the arm 45. The rod 41 is caused to reciprocate vertically by another cam 32^a on the shaft 31 operating a lever 410 and when it is shifted laterally as above described, it will raise the plate 43 and rod 44, thereby lifting the dog 50 45 into position to be engaged by a projection 46 on the lay 47 when the latter beats up on its forward motion. This causes the lay to move the dog 45 and rock arm 48 about a pivot 49 and thereby rock arm 50 and depress the transfferer 30 to force a bobbin from the box 24 beneath the transfferer down through the passage 27 in the plate 25 and into the shuttle. As the transfferer moves down it engages the trip 37, 55 that is under it, and returns it to its lowermost position. When these movements have been accomplished, one of the boxes 24 is left empty. For the purpose of filling the boxes a set of strips 53 and 53^a is employed, 60 one for each box. Each of these trips has a

freely swinging pendant 54 and 54^a, respectively, and the trips are attached to a slide bar 55 connected with the boxes 24 by arms 56 so as to travel with them, and are so positioned on the slide bar that the pendant corresponding with the box having the color of filling in use is located over the transfferer 30 so that the transfferer will engage the pendant for that color on its backward or upward movement (as shown in Figs. 2 and 70 4), raising the corresponding trip 53 or 53^a which is held in its raised position by friction and when it is moved opposite the compartment of the magazine that has that color of filling by the reciprocation of boxes 24 80 and bar 55 it engages the lower end of the catch 57 pivotally mounted on the bar 58 for that compartment of the magazine. The lower end of each catch 57 is beveled on its two front vertical edges so that endwise engagement of such catch by a trip 53 or 53^a will tilt the catch. One of these bars 58 is 85 slidably mounted alongside of each compartment of the magazine. When the catch 57 is rocked by the raised trip its upper end is 90 moved into the path of the corresponding arm 59 mounted on a rock shaft 63 controlled by a rod 62 operated by the cam 32 and lever 33, and the bar 58 to which said catch 57 is attached is thereby moved downwardly. The downward movement of this bar 58 causes the arm 60 pivoted to that bar to trip the cradle 61 and deposit a bobbin from that compartment of the magazine in the proper box 24, and at the same time the raised trip is pushed down to its normal position, as shown in Fig. 7.

The trips 54 and 54^a are so positioned on the bar 55, which moves with the boxes 24, 105 that, when a box 24 is under the transfferer in position to deliver its bobbin, its corresponding trip is above the transfferer in position to be raised by the transfferer on its return movement after it has transferred the bobbin from the box to the shuttle, and so that they will trip their respective catches 57 when the corresponding box is beneath that compartment of the magazine, as shown in Figs. 2 and 6.

110 It will be seen therefore that the action of transferring the bobbins is brought about in an exceedingly simple manner involving few parts and those of such a simple character that they do not afford great opportunity of getting out of order in practice and are 115 easily repaired in case of damage. Not a great deal of power is required to run them, and the expense of manufacture and running is greatly reduced.

120 Although we have illustrated and described a preferred embodiment of the invention, we are aware of the fact that the invention can be carried out with many changes in the details of construction without departing from 125 the scope of the invention as expressed in 130

the claims. Therefore we do not wish to be limited to all the details of construction herein shown and described, but

What we do claim is:—

- 4
- rod, means for reciprocating said rod once for each beat of the lay, said rod having means for moving the one of said trips which corresponds with the box that is under the transferrer, a second rod operable vertically synchronously with the first named rod, means in position to be operated by the trip which is operated by the first rod for moving the second rod laterally, a plate in position to be engaged by the second rod on its upward reciprocation when it has been so moved, means connected with said plate for causing the transferrer to be operated, and means automatically controlled by the transferrer for replenishing the box from the magazine after the transferrer has acted.
9. In a machine of the character described, the combination of a magazine, a set of reciprocable boxes and a lay, with means for transferring a bobbin from one of the boxes to the lay, means movable with said boxes for controlling the operation of said transferring means, and means for replenishing the box from the magazine.
10. In a machine of the character described, the combination of a magazine, a set of reciprocable boxes, and a lay, with means for transferring a bobbin from one of the boxes to the lay, and means controlled by the transferrer on its reverse stroke for replenishing the box from the magazine after the transferrer has completed its operation.
11. In a machine of the character described, the combination of a magazine, a set of horizontally and rectilinearly reciprocable boxes, and a lay, with means controlled by the boxes and operated by the lay for transferring a bobbin from one of the boxes to the lay, means for replenishing the box from the magazine, and means operated by the transferrer on its reverse stroke for setting the replenishing means into operative condition after the transferrer has completed its operation.
12. In a machine of the character described, the combination of a magazine, a set of reciprocatory boxes and a lay, with means controlled by the boxes and operated by the lay for transferring a bobbin from one of the boxes to the lay, a set of trips equal in number to the number of boxes, means for moving said trips along with the boxes, means on the transferrer for engaging and operating one of said trips at the end of the reverse motion of the transferrer, and means connected with each of said trips for discharging a bobbin from one of the compartments of the magazine.
13. In a machine of the character described, the combination of a magazine having a plurality of compartments, a set of boxes reciprocable under the magazine, a transferrer for transferring a bobbin from one of said boxes, a set of trips corresponding and movable with the boxes, means on the transferrer for actuating one of said trips corresponding with the box emptied by the transferrer upon the completion of the reverse motion of the transferrer, and means whereby on the next operation of the boxes the corresponding compartment of the magazine will deposit a bobbin in the box which has been emptied.
14. In a machine of the character described, the combination of a magazine having a number of compartments, a transferrer, a plurality of trips corresponding with the number of compartments in the magazine, means for moving said trips with the beat of the lay, means on the transferrer for engaging and raising one of said trips upon the reverse motion of the transferrer after it has acted, a bar, means for periodically raising and lowering the bar synchronously with the beat of the lay, a latch on the bar in position to be engaged by the trip which has been operated by the transferrer, and means connected with said latch for depositing a bobbin from one of the compartments of the magazine.
15. In a machine of the character described, the combination with a magazine having a plurality of compartments, of a bar thereon having a pivoted latch, a set of boxes movable with the lay, a set of trips carried with the boxes and adapted to engage and operate the latch, means movable with the lay for controlling the descent of said bar, an arm pivoted to said bar, a cradle, and connections from said arm to the cradle to operate the cradle and deposit a bobbin from the magazine in one of said boxes.
16. In a machine of the character described, the combination with a magazine having a plurality of compartments, of a bar thereon, a set of boxes movable with the lay, a trip movable with the lay into position for controlling the periodical descent of said bar, an arm pivoted to said bar, a cradle, connections from said arm to the cradle to operate the cradle and deposit a bobbin from the magazine in one of said boxes, and means for simultaneously pushing the trip that has been actuated back into normal position.
- In testimony whereof we have hereunto set our hands, in the presence of two subscribing witnesses.
